UNITED STATES PATENT OFFICE.

FREDERICK O. GUTMAN, OF CLEVELAND, OHIO, ASSIGNOR TO THE ROYAL MUSIC COMPANY, OF CLEVELAND, OHIO, A CORPORATION.

MUSICAL INSTRUMENT.

SPECIFICATION forming part of Letters Patent No. 775,817, dated November 22, 1904.

Application filed November 19, 1903. Serial No. 181,798. (No model.)

To all whom it may concern:

Be it known that I, FREDERICK O. GUTMAN, a citizen of the United States, and a resident of Cleveland, county of Cuyahoga, State of Ohio, have invented certain new and useful Improvements in Musical Instruments, of which I hereby declare the following to be a full, clear, and exact description, such as will enable others skilled in the art to which it appertains to make and use the same.

My invention relates to improvements in stringed musical instruments, such as a mandolin or guitar, having a neck and sounding-board; and the objects of the invention are to provide a body for the instrument made with an integral sounding-board and neck or stem; and it consists in the details of construction and combination and arrangement of parts, as hereinafter described, shown in the accompanying drawings, and specifically pointed out in the claims.

In the accompanying drawings, Figure 1 is a plan view of the device. Fig. 2 is a longitudinal central section thereof.

In the views, 1 is the body of the instrument, shaped from one integral piece of light and resonant wood, such as California redwood. The cavity 2 of the body is circular and is bored from the bottom toward the top, leaving a thin plate 3 at the top integral with the body and covering the opening. This forms the sounding-board. The usual opening 4 left in this board for sound emission is made at the end of the cavity 2, is circular also in shape, and is bored entirely through the wooden body. The bottom is then completed by gluing a thin plate of wood 5 over the opening thus formed in the body of the instrument.

The strings are stretched over the sounding-board upon a bridge 6 and secured in the usual manner at the lower end and are drawn over the metal frets 7 by means of the metal pins 8. The frets may be sunk in the stem just as it is formed, or a thin strip 9 may be glued upon the stem, in the upper surface of which the frets are secured.

The advantages of this unique form of construction are found in the unusual strength

of the instrument, its unity of tone, avoiding 50 all overtones, and the entire freedom from warping.

The primary advantage of boring the large hole part way through the body of the instrument, a thin sounding-board being thus 55 formed, is that the sounding-board can thus be made of uniform thickness throughout, which could not be accomplished by gouging or chiseling or any other well-known method. Great exactness is essential to a perfect vibration 60 of the sounding-board and a perfect quality of tone, as all manufacturers of musical stringed instruments are aware. Not only perfection of workmanship, but also economy 65 in manufacture is thereby obtained.

Having described my invention, what I claim as new, and desire to secure by Letters Patent, is—

1. In a stringed musical instrument, in combination, an integral body, stem and sounding-board, the said body and stem being formed of soft light and resonant wood, such as California redwood, a circular opening in the back having smooth sides and bottom, and the said bottom being a plane surface strictly parallel 70 with the plane of the upper surface of the instrument, and the said opening extending nearly to the upper surface of the instrument, an integral sounding-board being thus formed upon the front of the instrument, a smaller 75 circular opening or sound-hole bored entirely through the body portion, communicating with the larger opening, and a thin wooden plate closing both said openings, at the back of the body portion, substantially as described. 80

2. In a stringed musical instrument, in combination, a body portion and stem therefor formed of one integral piece of soft, light and resonant material such as California redwood, a circular sound-opening, having smooth sides, 90 and a perfectly flat bottom, extending from the back nearly to the front, a sounding-board being thus formed over the said opening, a smaller circular opening extending entirely through the said body portion from front to 95 back, a thin plate of wood forming the back of the instrument and covering both said openings, and a strip of hard wood covering

the front of the stem, substantially as and for the purpose set forth.

3. In a stringed musical instrument, a body portion composed of light and resonant material, in one integral piece, having a sound-opening therethrough, and a larger opening therein extending from the back nearly to the front, the sides and bottom of said opening being smooth, and the bottom being a plane surface, an integral sounding - board of un-

varying thickness throughout being thus formed on the front of the body portion, as and in the manner described.

In testimony whereof I hereunto set my hand this 17th day of November, 1903.

FREDERICK O. GUTMAN.
